UNITED STATES PATENT OFFICE.

WILLIAM V. OOTHOUT, OF BROOKLYN, ASSIGNOR TO G. L. KELTY & CO.,
OF NEW YORK, N. Y.

DESIGN FOR GIMP.

SPECIFICATION forming part of Design No. 11,977, dated October 12, 1880.

Application filed June 5, 1880. Term of patent 3½ years.

To all whom it may concern:

Be it known that I, WILLIAM V. OOTHOUT, a citizen of the United States, residing at the city of Brooklyn, in the county of Kings and State of New York, have invented and produced a new and original Design for Gimp, of which the following is a specification, reference being had to the accompanying drawing, which forms a part thereof, and represents a plan view of my newly-invented design for gimp.

The features of my design consist in a figure representing a series of slide-clasps having a central bar, the said slide-clasps being placed at equal distances from each other the entire length of the gimp, and being traversed by a belt or tape which passes under the ends of the slide-clasp and over the central bar thereof, nearly covering the said central bar, the plain edges of the body of the gimp projecting a little beyond the slide-clasps on each side.

A represents the slide-clasps having the

central bar, a. B is the tape or belt that passes through them, and C represents the body or ground of the gimp.

It is obvious that any combination of colors may be used to produce this design, or may be shown by the manner of weaving without the colors.

Having thus described my invention, what I claim, and desire to patent, is—

A design for gimp, consisting of a figure representing a series of slide-clasps, A, having a central bar, a, said clasps resting upon the face or body of the gimp at equal distances from each other its entire length, and traversed by a belt or tape which runs under the ends of the slide-clasp and over the central bar thereof, the plain edges of the body of the gimp projecting a little beyond the clasps on each side, substantially as shown.

WILLIAM V. OOTHOUT.
